UNITED STATES PATENT OFFICE.

BENJAMIN F. FIELD, OF LOS ANGELES, CALIFORNIA.

GAS-BURNER ATTACHMENT.

SPECIFICATION forming part of Letters Patent No. 511,518, dated December 26, 1893.

Application filed April 25, 1893. Serial No. 471,794. (No model.)

To all whom it may concern:

Be it known that I, BENJAMIN F. FIELD, a citizen of the United States, residing at Los Angeles, in the county of Los Angeles and 5 State of California, have invented certain new and useful Improvements in Gas-Burner Attachments; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 The object of my invention is to provide a gas-burner with more positive and sure mechanism for automatically and completely turning off the gas when the means for holding the burner-valve open, is released.

20 With such an object in view, my invention consists in the peculiar manner of constructing and arranging the different parts as will be fully described hereinafter and pointed out in the claim.

25 In the accompanying drawings: Figure 1 represents a perspective view of my improvement applied to an ordinary gas-burner; Fig. 2 a vertical section of the same, detached from the burner. Fig. 3 represents a top 30 view; Fig. 4 a sectional view taken on line X—X of Fig. 1.

The reference letter *a* represents a gas-burner of the ordinary type, provided with the usual valve-stem *b*. This valve-stem *b* 35 is provided with a laterally and downwardly extending arm *c* rigidly secured thereto and forming a shoulder against which one end of a coiled spring *d* abuts. This spring is confined within a circular casing *e* provided with 40 inwardly extending upper and lower flanges *f* and *g*. The valve-stem *b* is also provided with a hinged thumb-piece *h*, having an edge *l* arranged to engage a series of notches *i* in the inner edge of the upper flange *f*. By 45 means of this series of notches and the hinged thumb-piece *h*, the flow of gas may be regulated and the flame thus made dim or bright, according to the wishes of the operator.

On the interior of the casing *e* and at a point adjacent to the normal position of the lateral arm *c*, is secured a shoulder *k*, shown by full lines in Fig. 3, against which the fixed end of the coiled spring *d* bears. This shoulder is rigidly secured to the casing and forms a solid base for the spring to bear against. 50

Having described my invention in detail, I will now describe its operation.

I will assume that the flow of gas is cut off, and the thumb-piece *h* is therefore at right angles to the path of the gas; and it is 60 desired to turn on the gas in order to light the same. The thumb-piece is turned longitudinally with the path of the gas and then swung on its hinge until its edge *l* engages one of the series of notches *i* in the upper 65 flange *f* of the casing *e*, where it is held by said notches. The thumb-piece, and consequently the valve-stem, is turned against the tension of the coiled spring *d*, owing to the lateral arm *c* being rigid with the valve-stem. 70 Thus the cut-off is held by the notches *i* against the tension of the spring *d*. Now, if it is desired to turn out the gas, it is only necessary to swing the thumb-piece *h* clear of the notches *i*, and the tension of the spring 75 *d* will force the valve-stem around and across the path of the gas, thus effectively cutting off all escape of the same. It will be seen that there is no possible chance of the gas being allowed to leak by the carelessness of 80 the operator, for it is only necessary for him to release the thumb-piece from the notches in order to have the gas cut off.

It will be seen that if it is desired to turn on a partial flow of gas, it can easily be done 85 by allowing the edge *l* to engage any one of the series of notches *i*.

Having thus described my invention, what I claim as new, and desire to secure by Letters Patent, is—

The combination with a gas burner valve, 90 of a circular box embracing the stem and having a plane upper face, the inner edge of a portion of said face being ratcheted, a rigid arm in the valve stem and projecting 95 into the circular box, a coil spring in the box,

and connected to the arm whereby the valve is given a normal tendency to close, and a plate pivoted to the valve stem and capable of swinging to one side of the stem so as to lock with the ratchet teeth in the box, and thereby hold the valve in the desired position and to swing to the other side of the stem so as to engage the plane upper face of the box

and thereby allow the spring to close the valve, substantially as described.

In testimony whereof I affix my signature in presence of two witnesses.

BENJAMIN F. FIELD.
